UNITED STATES PATENT OFFICE

130,058

DESIGN FOR A COMPRESSOR

Frank A. Halleck, Oak Park, Ill., assignor to
Sullivan Machinery Company, a corporation of
Massachusetts

Application May 1, 1941, Serial No. 100,733

Term of patent 14 years

To all whom it may concern:

Be it known that I, Frank A. Halleck, a citizen
of the United States, residing at Oak Park, in
the county of Cook and State of Illinois, have
invented a new, original, and ornamental Design
for a Compressor, of which the following is a
specification, reference being had to the accom-
panying drawings, forming a part thereof,
wherein:

Fig. 1 is a perspective view of a compressor
showing my new design, the view showing the
front and one side of the compressor.

Fig. 2 is a top plan view of the compressor.

Fig. 3 is a front view of the compressor.

Fig. 4 is a side view of the compressor showing
the side thereof opposite the side which is prin-
cipally visible in Fig. 1.

Fig. 5 is a back view of the compressor.

I claim:

The ornamental design for a compressor, as
shown.

FRANK A. HALLECK.
